UNITED STATES PATENT OFFICE.

GEORGE E. ADAMS, OF PROVIDENCE, RHODE ISLAND.

DESIGN FOR A BUCKLE-PLATE.

SPECIFICATION forming part of Design No. 21,233, dated December 15, 1891.

Application filed November 17, 1891. Serial No. 412,208. Term of patent 7 years.

To all whom it may concern:

Be it known that I, GEORGE E. ADAMS, of Providence, in the county of Providence and State of Rhode Island, have invented and produced a new and original Design for Buckles, of which the following is a specification, reference being had to the accompanying drawing, forming part thereof.

The drawing is a view of the buckle, representing my new design.

The leading features of my design for buckles consist in the symmetrical outline of the buckle-plate and depending tongue, together with the ears extending below the diagonal portions of the buckle-plate.

Number 2 in the drawing indicates a buckle-plate having the upper straight edge 3 and the side edges 4 at right angles therewith, the surface of these sides being slightly curved toward the edges. From the lower ends of these sides the outline extends inward diag-

nally to meet the scrolled ornaments 5, thus exposing to view the ears 6, which form part of what is known as the "clamping-plate" of the buckle and is pivoted in bearings on the reverse side of the plate 2. The scrolled ornaments 5 have curved edges contracting to form the tongue 7, provided with the upwardly-bent lip 8, having a beaded edge.

Those portions of the scrolled ornaments 5 extending inward on the plate 2 meet the edges of the dart ornament 9 in the center of the plate, the lower part of this dart ornament extending down onto the spring-tongue 10, which is stamped out of the metal plate 2. 35

What I claim is—

The design for buckles, as herein shown and described.

GEORGE E. ADAMS.
